UNITED STATES PATENT OFFICE.

THOMAS KEPPEL NORTH, OF CRAYFORD, ENGLAND, ASSIGNOR TO VICKERS LIMITED,
OF WESTMINSTER, LONDON, ENGLAND.

BREECH-LOADING ORDNANCE.

1,326,213.

Specification of Letters Patent. Patented Dec. 30, 1919.

Application filed December 24, 1917. Serial No. 208,706.

To all whom it may concern:

Be it known that I, THOMAS KEPPEL NORTH, a subject of the King of Great Britain, residing at Crayford, in the county of Kent, England, have invented certain new and useful Improvements in or Relating to Breech-Loading Ordnance, of which the following is a specification.

This invention relates to ordnance breech mechanism of the carrier type in which the breech block is arranged outside the breech end of the gun barrel instead of within it as is usual and turns about the axis of the barrel in locking and unlocking it to and from the barrel. The invention is particularly although not exclusively applicable to ordnance intended for firing incendiary shells or so called rockets.

According to the invention the externally arranged breech block has a rearwardly extending axial stem rotatably mounted in the carrier and operated by the breech actuating hand lever through a non-rotary member slidably carried by the stem and connected thereto by one or more inclined or spiral grooves and keys. The said member, which is preferably in the form of a sleeve mounted on the stem, may be prevented from moving angularly about the axis of the breech block, 25 by the breech actuating hand lever. The aforesaid axial stem may be made hollow to receive a spring controlled striker carrying a transversely movable sear piece or plate which bears against a projection on the stem 30 to hold the striker in the cocked position but which, when displaced by the firing mechanism to fire the gun, assumes a position to liberate the striker. The said plate is caused to move angularly with the breech block 35 during the locking and unlocking displacements of the latter and is so arranged in relation to the member of the firing mechanism that serves to displace it to the firing position, that this member cannot actuate the plate unless the breech block is fully locked. The said member is preferably in the form 40 of a firing lever pivoted to a part recoiling with the gun barrel and is operated to fire the gun by a firing rod carried by a non-recoiling part. This arrangement of the firing lever on a recoiling part and the firing rod on a non-recoiling part facilitates the operation of the gun in that the firing rod, which is the part that is operated by the 45 gunner to fire the gun, does not partake of

the recoil and forward movements of the barrel. The said rod is so constructed and arranged that in the event of the barrel recoiling slightly as a result of a blow or jar, the firing lever (which moves with the barrel) will not be actuated to release the 60 striker.

In order that the said invention may be clearly understood and readily carried into effect, I will describe the same more fully 65 with reference to the accompanying drawings, in which:—

Figures 1, 2, 3, 4, and 5 are respectively a side elevation, a front elevation, a rear elevation (with the rear sight removed), a plan 70 and a vertical longitudinal section of a gun provided with a constructional form of my improvements. In Fig. 1 the firing mechanism is shown in the fired position but in Figs. 4 and 5 it is shown in the cocked position. 75

Fig. 6 is a horizontal section through the axis of the gun barrel showing the breech block carrier in the open position.

Fig. 7 is an enlarged view of the main 80 parts of Fig. 6.

Figs. 8 and 9 are enlarged views of parts of Fig. 5, and

Fig. 10 is an enlarged view of part of Fig. 3. 85

A is the gun barrel which in the example shown has connected thereto two guide members a' , a^2 disposed around or within guide tubes A' , A^2 attached to a trunnion block a^3 which is trunnioned in the crosshead or carriage A^3 of the mounting. B is the breech block which has a forwardly extending cylindrical flange b formed with interrupted internal collars of buttress formation which engage with corresponding collars on the outer surface of the breech end of the gun barrel. B' is the aforesaid rearwardly extending axial stem of the breech block, this stem being disposed in a collar c forming part of the carrier C which is connected by 90 a vertical pivot pin C' to lugs a^0 , a^0 on the rear one a^2 of the aforesaid guide members. 95

The means for operating the breech block comprise a sliding sleeve D mounted upon the aforesaid stem B' of the breech block 105 and connected thereto by one or more inclined or spiral grooves and keys. The sleeve is prevented from moving angularly about the axis of the breech block, so that when the sleeve is displaced along the stem, 110

angular locking and unlocking movement will be imparted to the breech block. To effect the said displacement of the sleeve, I employ an operating hand lever D' connected by a vertical pivot d' to the carrier C and arranged transversely to the axis of the gun barrel when the breech block is in its locked condition. This hand lever engages with the sleeve D, angular movement 10 of the hand lever thereby imparting axial movement to the sleeve to effect the angular locking and unlocking displacements of the breech block. The said hand lever may have a spherically shaped handle and may 15 be composed of two plates coupled together by suitable distance pieces d, d these plates being disposed in contact with flat surfaces one on the top and the other at the bottom of the sleeve (see Figs. 3 and 10) and engage 20 gaging with collars thereon. The engagement of the plates with the said flat surfaces prevents angular movement of the sleeve from occurring with respect to the gun barrel.

25 The carrier C is provided with a breech block retaining catch comprising a spring controlled plunger E which, when the breech block assumes its unlocked position, enters a hole in the breech block (see Figs. 6 and 30 7) and thereby prevents the latter from moving angularly about its axis when the carrier, by continued movement of the hand lever, is swung aside to enable the gun to be loaded. The breech block carries a second plunger e which, when the breech block 35 has become unlocked, bears against the inner end of the plunger E on the carrier and which, as the carrier is completing its closing movement, comes against the breech 40 face and thereby disengages the plunger E from its hole in the breech block which is then free to be locked to the gun barrel.

An extractor F in the form of a bell crank lever is mounted upon the pivot pin 45 C' of the carrier; the rear arm of the extractor lies transversely to the axis of the gun barrel (see Figs. 6 and 7) and is disposed in a groove in the breech face and the forward arm lies longitudinally with 50 respect to the barrel and is formed with a shoulder f against which the carrier bears, when the latter is approaching its fully swung out position, to actuate the extractor. Between the said longitudinal arm and the 55 gun barrel a spring f' is interposed.

G is the striker and G' is the striker spring both these parts being disposed in the hollow stem B' of the breech block. The spring is held in position by a screw 60 threaded plug or nut g through which the striker stem passes. G² is the aforesaid transversely movable sear plate which is slidably mounted in a cocking piece g' detachably connected to the rear part of the 65 striker stem and which, when the striker is

in the cocked position, bears against a rearwardly extending arm g² on the plug or nut g. This cocking piece has curved fins or lateral projections g'', g''' which fit in grooves in the stem of the breech block and 70 the sear plate is formed with an aperture g³ which, when the plate is displaced upward against the resistance of its spring, registers with the said rearwardly extending arm g² to enable the striker to be impelled forward by its spring to fire the gun. The cocking piece is moved rearward to cock the striker by the aforesaid sleeve D that is operated by the hand lever D', the rear face of the sleeve bearing against the 80 front face of the cocking piece g' to effect the cocking movement which thus takes place simultaneously with the unlocking movement of the breech block. H is the aforesaid firing lever for displacing the sear plate G² and K is the firing rod which has a tapered or conical end h for actuating this lever. The said firing lever is spring controlled and is pivoted to a sleeve a^{2x} carried by the rear one a² of the aforesaid guide 85 members connected to the gun barrel and is provided with a roller h adapted to come into contact with the lower face of the sear plate G², the cocking piece g' being formed with a slot g⁴ (Figs. 9 and 10) only slightly 90 wider than the roller, to enable firing movement of the roller to occur. When the breech block is in any but its fully locked position, the sear plate will be out of the path of the roller, and in consequence the 95 firing lever H cannot be actuated to fire the gun as the roller h at such time lies contiguous to the lower surface of the cocking piece on one side or the other of the slot 100 therein. The rod K has a thumb piece k' 105 situated between handle grips A^{2x}, A² attached to the rear one A² of the aforesaid guide tubes carried by the trunnion block a³ and its forward part is guided by part of the aforesaid sleeve a^{2x}. The tapered or 110 conical end of the said rod bears against a second roller h' on the firing lever H so that forward movement of the rod will actuate the firing lever to release the striker as aforesaid. In order to prevent the striker 115 from being released in the event of any blow or jar effecting a slight recoil movement of the gun and thereby causing the said second roller h' to run up the tapered or conical end of the rod K, the latter is formed with 120 a longitudinal safety groove K' in which the roller runs without actuating the firing lever if such slight recoil should occur. The provision of this safety groove renders it necessary to bring the groove out of line 125 with the roller to effect the release of the striker and for this purpose the rear end of the rod K is formed with a spiral groove K² with which engages a screw or stud K^{2x} (Fig. 8) on a fixed part; in this manner the 130

rod K during its forward or firing movement under the pressure of the gunner's thumb on the thumb-piece k' is angularly displaced about its axis to bring the safety groove K' out of line with the roller h'. The handle block is provided with a pivoted safety catch L which prevents the forward or firing movement of the thumb piece k' from occurring when the said catch occupies its safety position.

The safety catch L is pivoted on a pin l and is forced down toward the thumb-piece k' by the action of the helical spring K^x (Fig. 8) surrounding the rod K acting through a swinging block m pivoted on a pin n. This block bears against an extension or pin m^x projecting from the front surface of the catch above the pin l, so that the pressure of the spring K^x (which bears at its forward end against this block and at its rear end against the front part of the thumb-piece k') tends to hold the catch L in the position shown by Fig. 8 in which the rearward portion of the catch engages with a shoulder on the thumb piece k'. The safety catch L has one or more extensions l' (Figs. 1 and 4) arranged adjacent to the handle grips A^{2x}, A^{2x} so that when these grips are gripped by the gunner the forefingers of the hands come into contact with the projections l', thereby raising the catch L out of engagement with the shoulder on the thumb piece k'.

The rear sight M is mounted on the handle block and the front sight M' on the forward one a' of the aforesaid guide members connected to the barrel.

The forward guide tube A' connected to the trunnion block a³ constitutes a hydraulic brake cylinder in which is disposed a piston A⁴ whose rod is connected to the rear guide member a². The rear portion of this piston rod is formed with an axial hole a⁴ to accommodate the aforesaid rod K when the gun barrel recoils. A barrel return spring A⁵ is arranged around the front guide tube A' and bears at its front end against the forward guide member a' and at its rear end against the trunnion block a³. The said forward guide tube A' also carries a small ram a⁶ which, as the gun barrel approaches its forward or firing position after recoil, enters an axial hole a⁶ in the forward part of the piston rod to bring the gun barrel gently to rest by the displacement of the liquid from this hole through the restricted annular opening between the ram and the wall of the said hole.

What I claim and desire to secure by Letters Patent of the United States is:—

1. In ordnance breech mechanism, the combination with the gun barrel, the breech block arranged outside the breech end thereof, the carrier in which said block is mounted and the hand lever for operating

the breech mechanism, of a rearwardly extending axial stem on the breech block, said stem being rotatably mounted in the carrier, a non-rotary member slidably carried by said stem, means whereby actuation of the hand lever imparts longitudinal movement to said member and means between this member and the stem for causing the longitudinal movement of said member to impart angular movement to the breech block about its axis.

2. In ordnance breech mechanism, the combination with the gun barrel, the breech block arranged outside the breech end thereof, the carrier in which said block is mounted and the hand lever for operating the breech mechanism, of a rearwardly extending axial stem on the breech block, said stem being rotatably mounted in the carrier, a non-rotary member slidably carried by said stem, means whereby actuation of the hand lever imparts longitudinal movement to said member and an inclined or spiral groove and a key between this member and the stem for causing the longitudinal movement of said member to impart angular movement to the breech block about its axis.

3. In ordnance breech mechanism, the combination with the gun barrel, the breech block arranged outside the breech end thereof, the carrier in which said block is mounted and the hand lever for operating the breech mechanism, of a rearwardly extending axial stem on the breech block, said stem being rotatably mounted in the carrier, a member slidably carried by said stem, means whereby the hand lever prevents this member from moving angularly about its axis, means whereby actuation of said hand lever imparts longitudinal movement to said member and means between this member and the stem for causing the longitudinal movement of said member to impart angular movement to the breech block about its axis.

4. In ordnance breech mechanism, the combination with the gun barrel, the breech block arranged outside the breech end thereof, the carrier in which said block is mounted and the hand lever for operating the breech mechanism, of a rearwardly extending axial stem on the breech block, said stem being rotatably mounted in the carrier, a member slidably carried by said stem, means whereby the hand lever prevents this member from moving angularly about its axis, means whereby actuation of said hand lever imparts longitudinal movement to said member and an inclined or spiral groove and a key between this member and the stem for causing the longitudinal movement of said member to impart angular movement to the breech block about its axis.

5. In ordnance firing mechanism the com-

bination with the gun barrel, the breech block arranged outside the breech end thereof and the spring controlled striker carried by the breech block, of a transversely mov-
able sear piece carried by said striker, a projection on the breech block against which projection said sear piece bears to hold the striker in the cocked position and means for displacing said sear piece out of contact with the projection to release the striker for firing the gun.

6. In ordnance firing mechanism, the combination with the breech block and the spring controlled striker, of a transversely movable sear piece carried by said striker, means for causing this sear piece to move angularly with the breech block during locking and unlocking displacements of the latter, a projection on the breech block against which projection said sear piece bears to hold the striker in the cocked position, a member for moving the sear piece out of contact with the projection to release the striker for firing the gun, said member not moving angularly with the breech block, and means whereby unless the breech block is in its fully locked position, said member cannot operate the sear piece to release the striker.

7. In ordnance firing mechanism the combination with the gun barrel, the breech block and the spring controlled striker, of a sear piece carried by the striker, a part recoiling with the barrel, a firing member, mounted on said part, for operating said sear piece to release the striker, a part which

rod, mounted on the last stated part, for operating the firing member.

8. In ordnance firing mechanism the combination with the gun barrel, the breech block and the spring controlled striker, of a sear piece carried by the striker, a part recoiling with the barrel, a firing member, mounted on said part, for operating said sear piece to release the striker, a part which does not recoil with the barrel, a firing rod, mounted on the last stated part, for operating the firing member and means whereby when said rod is in its normal inoperative position, said firing member will not be operated thereby if the barrel moves rearward.

9. In ordnance firing mechanism the combination with the gun barrel, the breech block and the spring controlled striker, of a sear piece carried by the striker, a part recoiling with the barrel, a firing member, mounted on said part, for operating said sear piece to release the striker, a part which does not recoil with the barrel, a firing rod, mounted on the last stated part, for operating the firing member, a projection on said firing member against which said rod can bear when the latter is actuated, a longitudinal groove in said rod, which groove lies in line with said projection when the rod is in its normal inoperative position, and means whereby, when said rod is actuated to fire the gun, it is turned to bring the groove therein out of line with said projection.

In testimony whereof I hereunto affix my signature.

THOMAS KEPPEL NORTH.
